UNITED STATES PATENT OFFICE.

LEWIS W. EGGLESTON, OF BUFFALO, NEW YORK, ASSIGNOR TO AMERICAN RADIATOR COMPANY, OF NEW YORK, N. Y., A CORPORATION OF NEW JERSEY.

EXPANSIBLE COLLAPSIBLE ELEMENT.

Application filed August 8, 1923. Serial No. 656,446.

To all whom it may concern:

Be it known that I, LEWIS W. EGGLESTON, a citizen of the United States, residing at Buffalo, in the county of Erie and State 5 of New York, have invented new and useful Improvements in Expansible Collapsible Elements, of which the following is a full, clear, concise, and exact description, reference being had to the accompanying drawings, forming a part of this specification.

My invention relates to new and useful improvements in expansible-collapsible elements of that general character or type adapted to be subjected to pressure or thermal 15 static conditions for the purpose of operating a desired device or mechanism, which element consists of an annular or tubular shell of thin metal formed with circumferential corrugations comprising inner 20 and outer bends joined by intermediate wall portions extending in a general direction transversely of the element.

It is sometimes found that elements of the character mentioned are rendered inactive or inoperative, due to the fact that the metal of the bends of the corrugations is, through continuous use, or from being subjected to excessive pressures, fatigued to a point destroying the resilience of the 25 bends, and resulting in permanent collapse of the element at one or more points, thus reducing its useful life.

One object of the present invention is to obviate the objectionable result just stated, 30 by providing means for preventing collapse of the bends to such an extent as to result in destruction or reduction of the resilience of the element.

A further object is to provide such an element with means for limiting the collapsing movement thereof so as to prevent the same from being collapsed beyond a point which would subject the metal to deleterious strain, and finally result in permanent collapse, but which at the same time 45 would permit the element to have the desired extent of free movement for which it is designed.

A further object is to provide resilient 50 reinforcing means, which will not only prevent fatigue of the metal of the bends, but will also operate to maintain the annular contour of the element.

Other objects and the attending advantages will be apparent from the description 55 to follow hereafter.

The invention consists in the improvements to be more fully described herein-after, and the novelty of which will be particularly pointed out and distinctly claimed. 60

I have fully and clearly illustrated my invention in the accompanying drawings to be taken as a part of this specification, and wherein—

Figure 1 is a longitudinal central section 65 through a structure embodying my invention;

Fig. 2 is a section on the line 2—2 of Fig. 1;

Fig. 3 is an enlarged detail sectional view 70 of a portion of the wall shown in Fig. 1;

Fig. 4 is a view similar to Fig. 1, showing another embodiment of the same invention;

Fig. 5 is an enlarged detail view, similar 75 to Fig. 3, but showing a portion of the wall of the embodiment of the invention illustrated in Fig. 4, and

Fig. 6 is a detail plan view of a preferred form of an element employed in each of 80 the previous figures.

Referring to the drawings by characters of reference, A designates a preferred form of an expansible-collapsible element consisting of a tubular metal shell 1, substantially cylindrical in general contour. This shell 1 may be, and preferably is, closed at one end by an integral head 2, preferably in the form of a boss consisting of a transverse wall member 3 having a circumferential cylindrical flange portion 4, joining at its edge with the cylindrical shell 1 of the element. At its opposite end the element is provided with a longitudinal, cylindrical extension or flange 5, by which the element is adapted to be secured or attached to any suitable element or support (not shown). The head 2, heretofore mentioned, is preferably of thicker metal than that composing the cylindrical shell 1, and the annular portion 4 tapers into the metal of the shell, as indicated at 6. The element, in its preferred form, is composed of suitable metal or alloy, for example, copper, or alloy of copper and zinc, which, in its preferred embodiment, is drawn by suitable die mechanism

to a thickness approximately .007 of an inch. The body of the element, or the shell portion 1, is provided with circumferential corrugations 7, by which the element is 5 rendered longitudinally expansible and collapsible. These corrugations comprise alternate inward, flexible and resilient bends 8 and outward, flexible and resilient bends 9 connected by intermediate wall portions 10, the latter extending in a general direction transversely of the element. These corrugations, and the depth of the walls 10, are preferably proportioned according to the diameter of the element made. For example, in an element of $2\frac{7}{16}$ inches outside 15 diameter, the inside dimension or diameter of the element may be approximately 1.72 inches, and the depth of the corrugation .344 inches, the bends of the corrugations being curved and struck on a radius of approximately .045 inches.

While I show and describe a specific form of corrugated expansible-collapsible element as being one to which my invention is 25 readily applicable, I wish it understood that the invention is not limited thereto, the same being shown and described only for the purpose of disclosing a preferred embodiment of my invention.

30 The element above described is adapted to be subjected to either internal or external pressure, and is either collapsed or expanded, as the case may be, to actuate a desired device or mechanism, and it will be understood that the corrugations are so spaced that they will have the necessary resilience to ensure the element having the desired extent of movement when actuated, the resilience of the metal in the bends 8 and 9 of the 35 corrugations acting to return the element to a normal position or condition of rest.

According to my present invention, I provide means whereby the element is prevented from being collapsed to a point beyond 45 the normal limits of resilience of the corrugations, thereby preventing continued use or excessive pressures from fatiguing the metal to a point whereby the resilience is destroyed or weakened, or the corrugations 50 permanently collapsed, so as to interfere with the free or sensitive functioning of the element.

In the preferred embodiment, this means 55 consists of an annular member 11 arranged in the bend of a corrugation and maintained in contact with the central portion of the bend, as clearly indicated in Fig. 3 of the drawings. This member 11 preferably consists of an annulus or ring which is substantially circular in cross-section, and of a body diameter less than the transverse width of the bend of the corrugation, so that clearance spaces 12 are provided between the opposite sides of the faces of the ring 60 and the inner faces of the side portions of

the bends. The body thickness of the ring is such, that upon collapsing movement of the side portions of the bends, the inner faces of the latter will contact the opposite sides of the ring within the limit of resilience of the bend, thereby preventing excessive collapse of the corrugation, and, consequently, of the expansible-collapsible element, and also preventing fatigue of the metal in the bend of the corrugation. It 70 will be understood that the thickness of the member 11 will be determined and proportioned in accordance with the internal diameter of the bend of the corrugation to which it is to be applied. For example, in an element of the size heretofore mentioned, namely $2\frac{7}{16}$ inches, wherein the bend is formed on a radius of .045 inches, the body of the ring is preferably circular in cross-section, and is formed on a radius of approximately .040 inches, thereby providing a ring of a diameter approximately .080 inches.

80 The member 11 may be of any suitable material which will have the capability of 90 resisting or limiting the collapsing movement of the bend of the corrugation, but is preferably of a suitable metal, and in the preferred embodiment said member is in the form of a resilient split-ring, as indicated in 95 Fig. 6, whereby the member not only serves to perform the function heretofore described, but also exerts its force expansively, whereby said member is held in positive and proper relation against the inner face of the 100 bend of the corrugation. It is understood that this applies to the ring or member when inserted in the outward bend of a corrugation. In applying the reenforcing element 105 in its preferred form, the said ring is collapsed or sprung inward by any suitable means (as indicated in dotted lines in Fig. 6) against its natural resilience, until it is of a size which will permit its insertion in the open end of the expansible-collapsible 110 element, and said ring is then located opposite the entrance to the corrugation in which it is to be located, and is released, whereupon it springs outward toward its normal 115 position and automatically seats itself within the corrugation and against the inner face of the bend, as will be clear from Figs. 1 to 5.

120 In Fig. 4 the invention is shown applied to the inward bends of the corrugations, as well as the outward bends, and in this form the annular member 11 exerts its spring action inward instead of outward, as heretofore described. When the ring is to be applied to the inner corrugation, the ring is expanded or opened and passed around the element and located opposite the corrugation to which it is to be applied, whereupon it is released, and upon contraction seats itself 125 within the bend of the corrugation, as shown 130

in Figs. 4 and 5. When the reenforcing member is in the form of a split-ring, it is preferable to have the ends thereof come as close together as practicable when the ring is in position in the bend of the corrugation.

It is to be noted that in the preferred embodiment shown and described, the member may be collapsed to such an extent as to cause the adjacent corrugations to touch each other, but the curved portions of the bends will not be flexed or bent to such an extent as to exceed the limit of resilience and become permanently collapsed.

What I claim and desire to secure by Letters Patent of the United States is:

1. An expandible-collapsible element for pressure and thermostatic purposes, comprising a tubular metallic shell having circumferential corrugations formed of resilient inward and outward bends connected by intermediate transverse wall portions, and means located in certain of said bends to prevent collapse thereof in a direction longitudinally of the shell, said means comprising an annular member arranged in engagement with the inner face of the bend, said member being of such thickness in a direction lengthwise of said element as to provide clearance spaces between the said member and the lateral portions of the bend but adapted to be engaged by said lateral portions within the limit of resilience of the metal of the bend.

2. An expandible-collapsible element for pressure and thermostatic purposes, comprising a tubular metallic shell having circumferential corrugations formed of resilient inward and outward bends connected by intermediate transverse wall portions, and means located in certain of said bends to prevent collapse thereof in a direction longitudinally of the shell, said means comprising an annular member arranged in engagement with the middle portion of the inner surface of the bend, said member being circular in cross-section and of such thickness lengthwise of the element as to provide clearance spaces between the said member and the lateral portions of the bend but adapted to be engaged by said lateral portions within the limit of resilience of the metal of the bend.

3. An expandible-collapsible element for pressure and thermostatic purposes, comprising a tubular metal wall having circumferential corrugations formed of resilient inward and outward bends joined by intermediate wall portions, and a reenforcing member located in certain of said outward bends and in contact with the inner surface thereof, said member being of such thickness in a direction lengthwise of said element that the said intermediate walls are free to move within the elastic limits of said bends but are prevented from being moved toward

each other far enough to be collapsed permanently.

4. An expandible-collapsible element for pressure and thermostatic purposes, comprising a tubular metallic shell having circumferential corrugations formed of resilient inward and outward bends connected by intermediate transverse wall portions, and means located in certain of said bends to prevent collapse thereof in a direction longitudinally of the shell, said means comprising an annular member engaging the inner face of the bend and being circular in cross-section, the radius of the curve of the bend bearing the proportion to the radius of the cross-section of said member of approximately .045 inches to .040 inches.

5. An expandible-collapsible element for pressure and thermostatic purposes, comprising a tubular metallic shell having circumferential corrugations formed of resilient inward and outward bends connected by intermediate transverse wall portions, and means located in certain of said bends to prevent collapse thereof in a direction longitudinally of the shell, said means comprising an annular member engaging the inner face of the bend and being circular in cross-section, the radius of the curve of the bend being greater than the radius of the cross-section of said member.

6. An expandible-collapsible element for pressure and thermostatic purposes, comprising a tubular metallic shell having circumferential corrugations formed of inward and outward bends connected by intermediate transverse wall portions, and means located in certain of said bends to prevent collapse thereof in a direction longitudinally of the shell, said means comprising an annular member engaging the inner face of a bend, said member being resilient in a direction transversely of the element.

7. An expandible-collapsible element for pressure and thermostatic purposes, comprising a tubular metallic shell having circumferential corrugations formed of inward and outward bends connected by intermediate transverse wall portions, and means located in certain of said bends to prevent collapse thereof in a direction longitudinally of the shell, said means comprising an annular member engaging the inner face of a bend, said member being resilient in a direction transversely of the element and exerting its force to hold it in position in engagement with the inner face of the bend.

8. An expandible-collapsible element for pressure and thermostatic purposes, comprising a tubular metallic shell having circumferential corrugations formed of inward and outward bends connected by intermediate transverse wall portions, and means located in certain of said bends to prevent collapse thereof in a direction longitudinally

of the shell, said means comprising a resilient split-ring held by its resilience in engagement with the inner face of the bend.

9. An expansible-collapsible element for pressure and thermostatic purposes, comprising a tubular metallic shell having circumferential corrugations formed of inward and outward bends connected by intermediate transverse wall portions, and means located in certain of said bends to prevent collapse thereof in a direction longitudinally of the shell, said means comprising a resilient split-ring held by its resilience in engagement with the middle portion of the inner surface of the bend.

10. An expansible-collapsible element for pressure and thermostatic purposes, com-

prising a tubular metallic shell having circumferential corrugations formed of inward and outward bends connected by intermediate transverse wall portions, and means located in certain of said bends to prevent collapse thereof in a direction longitudinally of the shell, said means comprising a resilient split-ring held by its resilience in engagement with the middle portion of the inner surface of the bend, and said ring being of such thickness lengthwise of the element as to provide clearance spaces between the said ring and the lateral portions of the bends.

In testimony whereof I have hereunto subscribed my name.

LEWIS W. EGGLESTON.
